UNITED STATES PATENT OFFICE.

FRANCOIS NOËL HALARY, OF PARIS, FRANCE.

EVAPORATING APPARATUS.

Application filed June 2, 1922. Serial No. 565,829.

To all whom it may concern:

Be it known that I, FRANCOIS NOËL HALARY, of 2 Rue Saint-Martin, Paris, France, have invented Evaporating Apparatus, of which the following is a full, clear, and exact description.

The present invention has for its object an evaporating apparatus, the internal temperature of which can be controlled at will and can never reach a degree dangerous for the products to be dried.

This evaporating apparatus is combined in such a manner as to automatically ensure, within the compartments or chambers containing the products to be dried, from top downwards, a continuous circulation of air the speed of which may be increased or diminished at will.

The evaporating apparatus forming the subject-matter of this invention is essentially characterized by the combination of the following elements:

a. One or more independent chambers or compartments having at their upper part an adjustable hot air inlet orifice and at their lower part an exhaust orifice also adjustable.

b. A heater adapted to heat the air which is to circulate within these chambers or compartments.

c. A draught pipe into which open the exhaust orifices of the drying chambers or compartments and in which pass the combustion products of the furnace.

d. Chimney-hoods provided with draught nozzles arranged within the draught pipe at the level of each exhaust orifice, in such a manner that the circulation of the combustion products from the heater through these nozzles creates, within the drying chambers or compartments, a partial vacuum ensuring the evacuation of the air laden with moisture, and its replacement by hot and dry air, in an automatic, instantaneous and continuous manner.

By this combination, the moisture contained in the product to be dried is immediately evacuated in proportion as the evaporation takes place; in fact, in contact with the hot air passing downwardly through each of the compartments of the apparatus, the water contained in the product to be dried evaporates and the water

vapour thus formed having a greater density than that of hot air, is collected at the lower part of the compartment and is immediately sucked through the draught pipe.

The drying is thus effected in a very short time without necessitating a high temperature and by controlling the inlet and exhaust orifices, it is possible to obtain within the drying apparatus a temperature which never reaches a degree detrimental to the product to be dried.

For the reasons given above, the present type of drying apparatus is capable of being used with advantage for drying fruits, vegetables, linen, etc.

The present invention has moreover for its object the application to this system of evaporating apparatus of a heating device combined in such a manner as to permit the easy control of the temperatures of the chambers or compartments containing the products to be dried.

This heating device is essentially characterized by the following points:

a. A heating chamber provided with inner partitions forming baffle-plates arranged at the lower part of the evaporating apparatus and within which can circulate the combustion products of the furnace; this chamber opens, on the one hand, within the furnace and, on the other hand, under the lower draught hood of the draught pipe;

b. Another chamber on the top of the previous one, within which is heated the air which is to circulate within the evaporating apparatus;

c. A furnace arranged below the lower draught hood of the draught pipe and provided with a damper permitting to direct the whole or a part of the combustion products either in the heating chamber above set forth, or in the draught pipe.

In order that this invention may be clearly understood it will be described hereafter with reference to the accompanying drawing in which:

Figs. 1 to 4 illustrate a drying apparatus constructed in accordance with the present invention, for drying fruits and vegetables; Fig. 1 is a front elevation; Fig. 2 is a longitudinal vertical section; Figs. 3 and 4 are two vertical cross sections made respectively according to lines A—A and B—B of Fig. 2.

Fig. 5 illustrates in vertical section, on a smaller scale a drying apparatus for drying linen.

- Figs. 6 to 8 illustrate the application of 5 the heating device above set forth to a drying apparatus for drying linen; Fig. 6 is a vertical section made according to lines C—D, E—F of Fig. 8; Fig. 7 is a horizontal section made according to line G—G of 10 Fig. 6; Fig. 8 is a vertical cross section made according to line H—H of Fig. 6.

Fig. 9 shows the application of this heating device to a drying apparatus with multiple compartments.

- 15 The drying apparatus illustrated in Figs. 1 to 4 comprises an outer body or casing *a*, within which are arranged two vertical rows of compartments *b* completely independent from each other; within each of these compartments is arranged a tray *c* on which are placed the fruits or vegetables to be dried.

20 These compartments are limited on two opposite sides by the front and rear faces of the casing *a* and on their two other vertical sides by transverse partitions *d*, *e*.

- 25 The intervals respectively comprised between the partitions *d* and *e* and the adjacent sides of the casing *a*, constitute sheaths or conduits *f* through which is led the hot air which is to be admitted in the various compartments *b*, as will be indicated hereafter.

- 30 The interval comprised between the two transverse partitions *e* communicates through 35 its lower part and through its upper part with the atmosphere and constitutes a draught pipe *g* through which is evacuated the hot air laden with moisture taken from the products to be dried, as will be explained below.

- 35 In the transverse partitions *d* are provided, at the upper part of each of the compartments *b*, orifices *h* through which the hot air, fed by the conduits *f* is admitted in 40 the compartments *b*; each orifice *h* is provided with a shutter *i*, movable about an axis *j* and capable of being operated from the exterior by means of a handle *k*. On the other hand; in the transverse partitions *e* are provided, at the lower part of each compartment *b*, ventilating grates through 45 which are evacuated in the draught pipe *g* the hot air and the vapours formed by the water contained in the products to be dried; these grates can be uncovered or closed at will, either in totality or partially, by means of sliding dampers *m* provided with operating knobs *n* permitting to move them from the exterior.

- 50 Within the draught pipe are arranged, at the level of each superimposed row of compartments *b*, hoods *o* opening in each other and adapted to increase the draught and to facilitate the evacuation of the hot air and 55 vapours.

The air is admitted into the apparatus through tubes *p* opening, on the one hand, into the atmosphere and, on the other hand, through orifices *q*, into chambers *r* arranged between the lower face of the casing *a* and the bottom of the lower compartments *b*.

Any source of heat whatever, for instance, a gas pipe *s* perforated with holes, is arranged under the apparatus.

The casing is provided on its front face 75 with doors *t*.

The operation of this system of drying apparatus is as follows:

The air enters in the apparatus through the tubes *p*, in which it is heated by the gas pipe *s*. It then passes through the orifices *q*, circulates in the chambers *r*, and ascends in the conduits *f* which distribute it in the compartments *b* through the orifices *h*; the admission of this air into each of these compartments is controlled by means of the shutters *i*. The hot air passes through each compartment from top to bottom. Under the action of the heat of this air, the water contained in the product to be dried evaporates; the water vapour thus formed being heavier than the atmosphere of hot air of each compartment, collects at the lower part of the latter and is immediately sucked simultaneously with the hot air through the ventilating grates *l* by the hoods *o* of the draught pipe *g*. By operating the shutters *i* and the dampers *m* the rate of passage of the hot air through each of the compartments *b* can be controlled at will.

The hot air and vapours issuing through the grates *l* from each compartment *b* are drawn by the hoods *o* and finally evacuated in the atmosphere.

The type of evaporating apparatus which 105 has just been described may, conveniently, be used for drying fruits, for the purpose of preserving the same.

The fruits, owing to their treatment in the evaporating apparatus above described, 110 lose their moisture whilst preserving their qualities and their sweetness; it is moreover to be noted that during their treatment the fruits are not in contact with any obnoxious gas.

115 By the combination of the shutters *i* and dampers *m*, it is possible to previously heat the fruits in an enclosed atmosphere, so as to avoid these fruits being suddenly subjected, at the beginning of the operation, to the action of a stream of air which might produce a too rapid drying and cause the hardening of their envelope.

120 The present type of evaporating apparatus may also be used with advantage for drying vegetables, confectionery products, chemicals or pharmaceutical products, etc.

125 The present invention is moreover applicable for realizing drying apparatuses for linen.

Fig. 5 shows a method of construction of this type of apparatus.

In this case, the drying apparatus instead of presenting two series of superposed compartments, comprises two chambers b^2 occupying all its height and in which is hung the linen to be dried.

Hot air is admitted in each of these chambers through its upper part; in order to ensure the distribution of this air throughout the width of the chamber, the upper face of the latter is inclined and presents a succession of orifices v each provided with a deflector u . By means of this device, the hot air is 10 conveyed, as previously explained, through the tubes p , the chambers r , arranged between the lower bottom of the chambers b^2 and the face of the casing a , and the conduits f and is distributed through the orifices v and the 15 screens u on all the surface of the chambers b^2 . The evacuation of the hot air and vapours formed by the water contained in the linen to be dried, is effected through an orifice t provided at the lower part of each of the 20 chambers b^2 and issue in a draught pipe g . Hoods o , adapted as previously stated to increase the draught and to facilitate the 25 evacuation of the hot air and vapours in the atmosphere, are arranged at the upper and lower parts of this draught pipe.

This system of drying apparatus completely remedies the inconveniences presented by ordinary hot chambers used for drying linen. As is well known, these latter must be 30 brought to a high temperature usually exceeding 100° C., in order to permit the evacuation of the vapours; this high temperature has the disadvantage of baking the dirt which may be left in the linen if the latter has not been sufficiently rinsed and the linen keeps a disagreeable smell; besides a too great 35 heat produces the too rapid drying of the threads which causes a rapid wear of the linen. Moreover in the hot chambers, the linen runs the risk of being burned and even 40 sometimes fire breaks out.

On the contrary, by means of the present invention, the linen is dried in an atmosphere of hot air constantly renewed and which can never reach a dangerous temperature; consequently, all the inconveniences of the hot 45 chambers are thus done away with.

This system of drying apparatus may be devised so as to comprise either a single drying chamber or any number of chambers opening in a common exhaust conduit.

It may be constructed either of sheet-iron, in the case of evaporating apparatuses of small dimensions, or of reinforced cement or masonry, in the case of industrial apparatuses of large dimensions.

In the drying apparatus illustrated in Figs. 6 to 8, the air is heated, before its admission in the side conduits f , in a chamber p^2 , constituted by a double bottom of each of the

chambers b^2 . This chamber p^2 contains an inner partition p^1 forming a baffle-plate and opens in the atmosphere through an orifice provided with a valve p^2 or other member permitting to control the air admitted.

The air laden with water vapour issues at the lower part of each chamber b^2 through an orifice l provided with a damper m and opening below a draught hood o^2 surmounting by a draught pipe g^2 .

In this hood o^2 opens a draught nozzle o^1 surmounting a hood o^3 arranged above the furnace s^2 .

The combustion products from this furnace s^2 are used for heating the air admitted in the chambers p^2 : for that purpose, under each of these chambers p^2 , the apparatus has a heating chamber x provided with inner partitions x^1 forming baffle-plates communicating, on the one hand, with the interior of the furnace through an orifice x^2 and opening, on the other hand, through an orifice x^3 under the draught hood o^3 .

A damper y permits directing the whole or a portion of the combustion products of the furnace s^2 either into the heating chambers x or directly into the draught pipes g^2 .

As previously stated, the combustion products, owing to their passage from the draught nozzle o^1 into the draught pipe g^2 , create, in the space surrounding this draught nozzle, a partial vacuum producing a suction of the air laden with moisture which collects at the lower part of the drying chambers b^2 ; under the action of this suction, the air is automatically and continuously renewed in the drying chambers.

When the damper y is closed the whole of the combustion products of the furnace circulate in the heating chambers x before escaping in the draught pipe g^2 ; the apparatus thus gives the maximum of heat.

On the contrary, if this damper y is completely open, the whole of the combustion products of the furnace directly escape in the draught pipe g^2 without heating the air which is to circulate in the drying chambers or compartments.

By opening the damper y to a greater or less extent, it is possible to obtain various temperatures within the drying chambers or compartments.

It is moreover to be noted that by completely opening the damper y , it is possible to obtain, in a very short time, the cooling of the drying chambers by a rapid circulation of cold air.

Fig. 9 shows the application of the above described heating device to an evaporating apparatus having multiple compartments, constituted as previously set forth.

It is to be understood that in this heating device it will be possible to employ furnaces of any system using solid or liquid fuels.

The shape, dimensions, constructional details and nature of the materials used will be modified according to the applications.

Claims:

1. An evaporating apparatus comprising independent compartments for containing the material to be dried, having at their upper parts hot air inlet orifice and at their lower parts exhaust orifice, a heater for heating the air which is to circulate within these compartments, conduits conducting the hot air to the inlet orifices, a draught pipe in which open the exhaust orifices of the said compartments and draught nozzles arranged within the draught pipe, at the level of the exhaust orifices of the compartments, so that the circulation of the heated air through these draught nozzles creates, within the drying compartments, a partial vacuum ensuring the evacuation of the air laden with moisture and its replacement by hot and dry air in an automatic, instantaneous and continuous manner. 40
2. An evaporating apparatus comprising independent chambers having inlets at the upper portion and outlets at the lower portion, a heater, conduits for leading the hot air to the inlets of the chambers, a draught pipe into which the outlets of the chambers open, and hoods in the draught pipe and provided with draught nozzles. 45
3. An evaporating apparatus comprising independent chambers having inlet openings in their upper portions, and exhaust openings at their lower portions, a draught pipe between the chambers and having nozzles 50
4. In an evaporating apparatus, independent chambers having inlet openings in their upper portions and exhaust openings in their lower portions, a draught pipe between the chambers and having nozzles arranged therein at the exhaust openings of the chambers, air pipes below the chambers communicating with the air pipes and leading to the inlet openings of the chambers, a heater, and means whereby the products of combustion may be utilized for heating the air pipes. 55
5. In evaporating apparatus, independent chambers having inlets in their upper parts and outlets in their lower parts, a draught pipe between the chambers and having nozzles therein at the outlet of the chambers, said pipes being each provided with a baffle, and a valve controlling the admission of air thereto, a heater, a heating chamber communicating with the heater and with the draught pipe, and a valve for permitting the products of combustion to enter the draught pipes or the air pipes. 60

The foregoing specification of my evaporating apparatus, signed by me this 10th day of May, 1922.

FRANÇOIS NOËL HALARY.
